J. W. REMBE.

SOAP POWDER DISPENSER.

APPLICATION FILED NOV. 28, 1919.

1,383,664.

Patented July 5, 1921.

Inventor:
John Walter Rembe,
by his attorney,
Charles R. Searle.

UNITED STATES PATENT OFFICE.

JOHN WALTER REMBE, OF JERSEY CITY, NEW JERSEY.

SOAP-POWDER DISPENSER.

1,383,664.

Specification of Letters Patent. Patented July 5, 1921.

Application filed November 28, 1919. Serial No. 341,000.

To all whom it may concern:

Be it known that I, JOHN WALTER REMBE, a citizen of the United States, residing at Jersey City, in the county of Hudson and 5 State of New Jersey, have invented a certain new and useful Improvement in Soap-Powder Dispensers, of which the following is a specification.

The invention relates to devices for supplying soap-powder to individual users in the small quantities required for toilet purposes in public lavatories and like situations, and the object of the invention is to provide a device of this character which shall be neat 10 and attractive in appearance, easily and economically manufactured and installed, and which shall be reliable in operation, discharge without waste, and locked with sufficient security to prevent the removal of the 15 powder except in the small quantities required for lavatory purposes.

The invention consists in certain details of construction by which the above objects are attained, to be hereinafter described and 20 claimed.

The accompanying drawings form a part of this specification and show the invention as it has been carried out in practice.

Figure 1 is a front elevation of the improved dispenser. Fig. 2 is a vertical section taken on the line 2—2 in Fig. 1. Fig. 3 is a plan view corresponding to Fig. 1. Fig. 4 is a plan view of the operating mechanism, with the reservoir or powder container removed.

Similar letters of reference indicate the same parts in all the figures.

A is the conical body portion of a casing containing the dispensing mechanism, having a laterally extending flanged bracket A¹ adapted to be secured to the wall above or in the immediate vicinity of the hand-basin, not shown, and a depending tubular extension A² through which the powder is delivered.

The upper portion of the body is screw-threaded internally to receive corresponding threads on the annular depending rim B¹ of a cylindrical container or reservoir, preferably of glass, adapted to contain a supply of soap-powder, and permanently joined to the body A by applying cement to the screw-threads and screwing the parts together as will be understood.

On the upper end of the reservoir B is a vertical annular flange or neck B² through

which the powder is introduced. It is closed by a metal plug C having a horizontal flange C¹ adapted to apply upon the neck B² and terminating below in an angular rabbet c. 60 Extending axially through the plug is a bolt D screw-threaded at the lower end and engaged in a circular disk or follower D¹, serving as a nut, through which the bolt extends and is headed beneath as at D² to prevent its removal. 65

The plug is countersunk to receive the head D³ of the bolt, and the latter is turned by the insertion of a key, not shown, in the recesses d in such head.

An annular gasket E of soft vulcanized rubber, preferably of circular cross-section, is engaged in the rabbet c between the plug C and follower D¹, adapted to be inserted with the plug and expanded by compressing it between the follower and plug through the medium of the bolt D, thus engaging it beneath the shoulder b and holding the plug against withdrawal until the key is again applied and the bolt slackened to permit the 70 gasket to contract. 75

The metal plug and glass container are thus strongly locked together without danger of fracturing the glass.

Across the interior of the body A extends 85 a bar F having a central hole f serving as a guide for a vertical valve-rod G extending axially through the delivery aperture a at the bottom of the body. At the top of the rod is riveted an agitator G¹ of sheet metal, 90 having radial arms, preferably in the form of a cross, and at the lower end below the aperture a the rod carries a conical valve G² adapted to control the aperture and the escape of powder therethrough.

Between the bar F and agitator G and abutting against these parts is a helical expansion spring G³ inclosing the valve-rod and tending to raise the valve G² to close the aperture a.

Riveted on the lower end of the rod G is a forwardly projecting arm G⁴ extending through a vertical slot a¹ in the extension A² and terminating in a finger-piece G⁵ by which the rod may be depressed to open the aperture a and permit a portion of the powder to escape through the extension A² to the hand of the user held below such extension.

The amount delivered is determined by the position of a collar G⁶ on the rod G below the bar F and arranged to approach the aperture a from above when the rod is fully 100 105 110

depressed but not to close such aperture entirely or pack the powder immediately above the aperture.

The action of the agitator G¹ is to prevent 5 the formation of a bridge in the powder above the bar F, which might otherwise form and interfere with delivery. The arms of the agitator by reason of the vertical reciprocations of the rod G stir the mass in the 10 container B and insure its maintenance in the desired loosely powdered condition.

The body A of the casing, with the bracket A¹, extension A² and bar F, is preferably a single integral casting as shown.

15 I claim:—

The herein described powder distributor comprising a reservoir and a casing separably formed and connected to the lower end

thereof, a transverse bar in the upper end of said casing, there being a valve seat in 20 said casing below said bar, and a tubular extension depending below said valve seat, a vertically disposed valve rod movable through said bar and through a delivery aperture at said valve seat, an agitator carried 25 by the upper end of said rod, a collar on said rod between said bar and valve seat, a spring on the rod between said agitator and bar, a valve on said rod upwardly movable to close said aperture, and an operating arm 30 connected with said rod and operable through a vertical slot in said depending extension.

In testimony that I claim the invention above set forth I affix my signature.

JOHN WALTER REMBE.
